UNITED STATES PATENT OFFICE.

SAMUEL A. NEIDICH, OF EDGEWATER PARK, NEW JERSEY, ASSIGNOR TO THE AMERICAN MULTIGRAPH COMPANY, OF CLEVELAND, OHIO, A CORPORATION OF OHIO.

PRINTING FEEDING MECHANISM.

1,089,150.

Specification of Letters Patent.

Patented Mar. 3, 1914.

Original application filed September 28, 1910, Serial No. 584,202. Divided and this application filed September 3, 1911. Serial No. 848,827.

To all whom it may concern:

Be it known that I, SAMUEL A. NEIDICH, of Edgewater Park, in the State of New Jersey, have invented a certain new and useful

5 Improvement in Printing Feeding Mechanism, whereof the following is a specification, reference being had to the accompanying drawings.

This application is a division of application Serial #584,202, filed September 28, 10 for Letters Patent of the United States for improvement in duplicating machines.

As hereinafter described, my invention includes mechanism for gripping and feeding 15 sheets of paper including an adjustable operating cam, adjustable rollers and paper stop fingers and is embodied in a machine comprising a rotary printing drum and a co-operative rotary platen; said drum being 20 adapted to print from type set in a flexible chase detachably held on said drum.

My invention includes the various novel features of construction and arrangement hereinafter more definitely specified.

25 In the drawings:—Fig. I is a fragmentary elevation of the left hand side of a duplicating machine embodying my invention. Fig. II is a fragmentary vertical sectional view of the left hand side of said machine. 30 Fig. III is a cross section through the actuating cam, as indicated by the line III—III on Fig. I.

In said figures; the duplicating machine frame 1 supports mechanism to feed the 35 paper 6 including the feed table 7 beneath the rotary printing drum 8. Said drum has its shaft 9 journaled in bearings in said frame 1 and having at one end the operating handle 12 exterior to said frame and at 40 its other end the collar 13 with the crown clutch teeth 14 engaging the crown clutch teeth 15 in the rotatably adjustable cam 16 which controls the paper feed. Said cam has the high portion 17, and is conveniently 45 provided with the knob flange 19 and the circumferential series of graduations 21 to facilitate its rotary adjustment with respect to said drum, being rigidly connected with said drum shaft 9 by the screw 22 and washer 23 shown in Fig. I. The gear 86 on said printing drum 8 engages the gear 171 50 to rotate the platen 172 having the rubber face 173 in co-operative relation with said drum. However, said drum and platen may

be rotated by the gear 147 on the main driving shaft 148; the latter being connected with a motor.

The paper feeding mechanism includes the feed roller 200 above the table 7, journaled in the frame 1, having at one end the 55 rotatably adjustable eccentric bearing 201, being idly rotary with its axis stationary parallel with said drum shaft 9. Said roller 200 has high sections spaced by reduced portions and is opposed by and driven by the pressure of the feed roller 203 below said table 7, having correspondingly spaced sections on the shaft 204, with rubber faces 205 to engage the paper 6. Said roller 203 is raised to co-operative relation with said 60 roller 200 by the rock shaft 208 having two lever arms 209 in which said shaft 204 is journaled, and the spring 210 tending to turn said shaft in the direction of the arrows. One end of said spring 210 being 65 connected to said shaft 208 and the other end to the bushing 206 as indicated in dotted lines in Fig. I, the torque on said shaft may be varied by rotary adjustment of said bushing in the frame 1, in which it is normally held stationary by the set screw 207. Said arms 209 also carry the cross bar 211 70 having the paper stop fingers 212 in registry with openings in the guide plate 213 and table 7, so that when said arms 209 are 75 lowered each paper sheet 6 may be thrust against said fingers to insure its proper angular relation with the machine before being gripped by the upward movement of said roller 203 against the roller 200. Said 80 stop fingers 212 are raised from engagement with the paper sheet 6 when the latter are thus gripped, and, said roller 203 is positively rotated by its gear 214 which is connected with the gear 171 by the idle gear 85 215 which turns loosely on said shaft 208. Said shaft 208 is turned against the pressure of said spring 210 to lower said roller 205 and stop fingers 212 by the arm 216 90 having the stud shaft 217 extending through the slot 218 in the frame 1 and carrying exterior thereto the friction roller 219 in position to be encountered by the high portion 17 on the cam 16. The discharge of the 95 printed sheets 6 from between said drum 8 and platen 172 is facilitated by the sectional 100 rollers 221 on the shaft 144, each having a corrugated rubber face 222 upon which the 105

sheets rest and are directed from the printing couple. Said shafts 200 and 208 are respectively provided with the normally stationary but rotatably adjustable eccentric 5 bearings 201 and 206 so that said shafts may be adjusted in precisely parallel relation with the axis of the printing drum 8, and, it may be observed that such construction not only simplifies and facilitates the primary 10 assembling of the machine but affords means to compensate for wear of the respective shafts, bearing and rollers.

The mechanism above described may be operated as follows: The type 25 are set 15 in the desired form in the flexible chase including the parallel channel bars 26 maintained in parallel relation by the flexible bands 27 connected with the opposite end attaching plates 28 and 29 shown in Fig. II 20 attached to the drum 8 and covered with the ink transfer sheet 50. The sheets of paper 6 of the selected size being directed in the desired relation to the width of said type form, the cam 16 is rotatably adjusted on 25 said drum 8 so that when each sheet 6 is presented against the stop fingers 212 it will be gripped at the proper instant to be drawn between said drum 8 and the platen 172 in such relation as to locate the printed impression thereon in the desired position with respect to the length of said sheet. A sheet of paper 6 being then inserted over the table 7 beneath the guide plate 214 against the stop fingers 212, and, said drum 8 being turned in 30 the direction of the arrow marked thereon, said feed roller 203 grips said sheet 6 against the feed roller 200, to draw it between said drum 8 and platen 172, print it, and discharge it over the rollers 221.

35 I do not desire to limit myself to the precise details of construction and arrangement above described as it is obvious that various modifications may be made therein without

departing from the essential features of my invention as defined in the appended claims. 45

I claim:

1. The combination with a frame, of a printing couple including a rotary drum having a shaft journaled in said frame, a cam on the end of said shaft outside of the frame, means whereby said cam may be rotatably adjusted and secured in rigid relation with said shaft, paper-feeding mechanism including a supporting table, a feed-roller above said table having a shaft with a 50 normally stationary axis, a feed roller below said table, and means arranged to shift said lower roller to and from co-operative relation with said upper roller, including a rock shaft carrying said lower 55 roller, and an arm rigid on the rock-shaft and located within the frame, and a roller on the outside of the frame coacting with the cam and connected with the arm through a slot in the frame.

2. The combination with a frame having a pair of upright plates, a shaft journaled in said plates, a printing drum on said shaft between said plates, the shaft extending through one of the plates, a cam adjustably 60 positioned on the end of said shaft, a paper table, a rock-shaft below the table, an arm on said rock-shaft lying between the frame plates, a roller on the outside of one of the frame plates connected with said arm 65 through a slot in the plate and coacting with the cam, and paper-feed mechanism controlled by said rock-shaft.

In testimony whereof, I have hereunto signed my name at Burlington, New Jersey, 80 this sixth day of September, 1911.

SAMUEL A. NEIDICH.
